ONE-HALF TO NOEL W. WYATT AND OLAF BAKER, BOTH OF MIAMI, OKLAHOMA.

VALVE.

1,405,631.

Specification of Letters Patent.

Patented Feb. 7, 1922.

Application filed May 31, 1921. Serial No. 473,956.

To all whom it may concern:

Be it known that we, EDWARD W. SCRIBNER and ROY DEPEE, citizens of the United States, residing at Douthat in the county of 5 Ottawa and State of Oklahoma, have invented certain new and useful Improvements in Valves, of which the following is a specification.

This invention relates to automatic control 10 valves, and more particularly to valves adapted to be arranged in gas lines and maintained in open position by the pressure of the gas when it exceeds a predetermined amount, but adapted to close below a pre- 15 determined point.

In the present invention, we have provided an automatic valve of this type wherein a pivoted trough or guide member is employed, the pivoted trough being maintained in 20 raised position by the pressure of the gas. When the gas pressure lowers, the weight of one end of the trough causes it to lower and a ball valve arranged therein is delivered to a valve seat in the gas line, a 25 valve seat being arranged in alinement with the end of the trough.

It is an object of the present invention to provide a valve of this type of simple construction and relatively few parts.

30 It is a further object to provide a valve that will be positive in operation and will close as soon as the gas pressure ceases or diminishes below a desired point.

In the accompanying drawings, we have 35 shown one embodiment of the invention. In this showing:

Figure 1 is a central vertical longitudinal sectional view,

40 Figure 2 is a transverse vertical sectional view on line 2-2 of Figure 1,

Figure 3 is a detail view of the pivoted trough, and,

Figure 4 is a similar view of the trough actuating member.

45 Referring to the drawings, the reference numeral 1 designates the valve chamber, which may be substantially semi-cylindrical in shape, as shown, and provided with a cover plate 2. The cover plate is retained in 50 position by bolts 3, permitting easy access to the interior of the valve chamber.

The inlet pipe 4 extends longitudinally of the valve chamber near the bottom thereof, the inlet pipe being provided with an opening 5 communicating with the valve cham-

ber. At the opposite end of the chamber, an outlet pipe 6 is provided, the inner end of the outlet pipe being arranged at an angle, as at 7, and provided with an end closure 8 having a valve seat 9 formed therein. The 60 end closure is provided with a central opening 10.

The pivoted trough 11 is provided with a pair of ears 12, arranged adjacent one end for the reception of a pivot pin 13. The end 65 of the trough adjacent the pivot is closed by an inlet 14. Adjacent the other end of the trough, there is provided a plate 15 of substantial area which is positioned over the opening 5 in the inlet pipe whereby the pressure of the incoming gas is exerted to maintain the trough in the operative, dotted line position shown in Figure 1 of the drawings. A crank 16, mounted on a shaft 17 is arranged in the bottom of the casing to permit 70 seating of the valve when the gas pressure has been cut off. The crank 16 is adapted to engage the plate 15 and the shaft 17 is provided with an operating handle 18. As shown, the shaft extends through a packing 75 gland 19. Means are provided for returning the ball to the trough when the valve is to be reseated. As shown, a chamber 20 is arranged in alinement with the inner end 7 of the outlet pipe and a rod 21 extends through 80 this chamber to a position adjacent the opening 10. A spring 22 is arranged in the chamber, one end of the spring abutting the bottom wall 23 thereof, and the other end being secured to the rod. The end of the 85 chamber is closed by a nut or sleeve 24, having a packing nut 25 arranged thereon.

A ball valve 26 is arranged in the trough 11 and is adapted to rest upon the valve seat 9 when the parts are in the position shown 90 in Figure 1 of the drawings.

In operation, with the parts in the position shown in Figure 1 of the drawings, when the valve is to be opened, the rod 21 is first pushed inwardly to lift the ball valve 100 into the end of the trough. The shaft 17 is then turned and the crank 16 engages the plate 15 to raise the trough to the dotted line position shown. The relative size of the parts and the arrangement of the pivot 105 is such that the trough will be retained in raised position by the pressure of the gas when the pressure is equal to or greater than the predetermined minimum and gas flows through the opening 10 into the outlet pipe. 110

As soon as the flow of gas ceases, or falls below the point of safety, the weight of the large end of the trough is sufficient to cause the trough to move to the full line position, 5 and the ball valve 26 assumes a position shown on the valve seat closing the valve.

It is to be understood that the form of our invention herewith shown and described is to be taken as a preferred example of the 10 same, and that various changes in the shape, size, and arrangement of parts may be resorted to without departing from the spirit of the invention or the scope of the subjoined claims.

15 Having thus described our invention, we claim:

1. An automatic gas valve, comprising a casing having an inlet and an outlet, a trough pivotally mounted in said casing and 20 normally assuming a lowered position, a plate secured to said trough, said plate being disposed in the path of gas passing through the casing whereby the trough is maintained in raised position by the flow 25 of gas, a valve seat arranged on said outlet, and a ball valve arranged in said trough adapted to engage said seat when the trough is in lowered position.

2. An automatic gas valve, comprising a 30 casing having an inlet and an outlet, a trough pivotally mounted therein, a plate secured to said trough, said plate being arranged in the path of travel of the gas whereby the trough is maintained in raised 35 position by the flow of gas, a valve seat arranged on said outlet, a ball valve arranged in said trough and adapted to engage said seat when the trough is in lowered position, and means for manually raising said trough 40 to permit flow of gas.

3. An automatic gas valve comprising a 45 casing having an inlet and an outlet, a trough pivotally mounted in said casing and normally assuming a lowered position, a plate secured to said trough, said plate being disposed in the path of gas passing through

the casing whereby the trough is maintained in raised position by the flow of gas, a valve seat arranged on said outlet, a ball valve arranged in said trough and adapted 50 to drop into and engage said valve seat when the trough is in lowered position, and means for returning said ball valve to said seat.

4. An automatic gas valve comprising a 55 casing having an inlet and an outlet, a trough pivotally mounted in said casing and normally assuming a lowered position, a plate secured to said trough, said plate being disposed in the path of gas passing 60 through the casing whereby the trough is maintained in raised position by the flow of gas, a valve seat arranged on said outlet, a ball valve arranged in said trough and adapted to drop into and engage said valve 65 seat when the trough is in lowered position, means for returning said ball valve to said trough, and means for manually raising said trough to permit the flow of gas.

5. An automatic gas valve comprising a 70 casing having an inlet and an outlet, a trough pivotally mounted in said casing and normally assuming a lowered position, a plate secured to said trough, said plate being disposed in the path of gas passing 75 through the casing whereby the trough is maintained in raised position by the flow of gas, a valve seat arranged on said outlet, a ball valve arranged in said trough and adapted to drop into and engage said valve 80 seat when the trough is in lowered position, and a manually operated plunger having its inner end normally disposed beneath said valve and adapted upon actuation to return said plate to said trough.

85 In testimony whereof we affix our signatures in presence of two witnesses.

EDWARD W. SCRIBNER.
ROY DEPEE.
